DRIVING MECHANISM FOR CENTRIFUGAL SEPARATORS

John F. Tholl, Needham, Mass., assignor to American Tool & Machine Co., Hyde Park, Boston, Mass., a corporation of Massachusetts

Application August 23, 1938, Serial No. 226,223

14 Claims. (Cl. 210—71)

This invention relates to centrifugal separators and is more especially concerned with the mechanisms for driving machines of this type.

As is well understood by those skilled in this art, such machines are commonly operated by two general types of drives, one consisting of an individual drive in which each machine is equipped with its own motor, and the other being the so-called "gang drive" in which a series of separators arranged in a line are operated from a single motor or other prime mover. While each has its advantages, the latter is generally preferred where machines can be operated in gangs due both to the lower initial expense for the driving equipment and also because of its greater economy in operation.

The present invention has for its general object to improve these driving mechanisms with a view to retaining the advantages of the gang type of drive while, in addition, providing for a positive slow speed operation of the centrifugals during discharging and affording the flexibility and independence of control which is desirable in the operation of the individual machines.

The nature of the invention will be readily understood from the following description when read in connection with the accompanying drawings, and the novel features will be particularly pointed out in the appended claims.

In the drawings:

Figure 1 is a plan view of a mechanism provided by this invention for driving a series of centrifugals;

Fig. 2 is a side elevation of the arrangement shown in Fig. 1;

Fig. 3 is an end view of said arrangement;

Fig. 4 is a vertical, longitudinal, sectional view of the driving arrangement for the first machine of the series shown in Figs. 1 and 2, it being understood that this arrangement is duplicated for each additional machine.

Fig. 5 is a vertical, sectional view showing a slightly modified form of transmission mechanism, and illustrating additional details of the connections between such a mechanism and the basket;

Fig. 6 is a sectional view approximately on the line 6—6, Fig. 5;

Fig. 7 is a vertical, sectional view through the flexible coupling shown in Fig. 5 and the parts immediately above and below it, but on a somewhat larger scale; and

Fig. 8 is a sectional view approximately on the line 8—8, Fig. 7.

Referring first to Figs. 1 and 2, the first two

centrifugal separators of a line of these machines, which may include any suitable number, are indicated, respectively, at A and B. These machines are all arranged in a straight line and are driven by a single electric motor 2 connected by the belt 3, Figs. 1 and 3, to a pulley 4 fast on a main driving shaft 5 which extends above and parallel to the entire line of machines.

Connecting the different machines with the shaft 5 are a series of driving mechanisms, one for each machine, so that the drive of any machine is independent of all the others. Each of these mechanisms is constructed and arranged to drive its respective centrifugal at both a high speed and a low speed, and controlling means is provided to shift the drive of any machine from one of said speeds to the other, at will, without disturbing the operation of any other machine in the series.

Fig. 4 shows in considerable detail a two-speed transmission mechanism of a novel construction for driving the vertical shaft 6 of the first centrifugal separator A. As will be evident from the other views, each of these machines is of the upright suspended type. Also, each is equipped with its own brake mechanism, the brake drum for the first machine being shown in Fig. 4 at 7 secured directly on the operating shaft 6. The upper end of this shaft has a bevelled pinion 8 secured to it and driven by a bevel gear 10 keyed to a sleeve 12 through which the main shaft 5 extends. This sleeve is, in effect, a supplemental shaft which may be connected with the main shaft 5 to be driven thereby through either of two clutches indicated, in general, at 13 and 14, respectively. The former, when in operation, is driven at the speed of the main shaft 5 and the latter through a reduction gearing 15 at a greatly reduced speed. Consequently, the clutches may be utilized selectively to drive the basket of the centrifugal at either a high operating speed or a low discharging speed.

The clutch 13 includes a clutch drum 16 mounted on a ball bearing unit 17 to revolve around the main shaft 5, and the hub portion 18 of the clutch extends toward the right, Fig. 4, and is keyed to the bevel gear 10. This gear is clamped against the hub part 18 by nuts 20 threaded on the sleeve 12. Thus, all of these parts are compelled to revolve in unison around the axis of the main shaft. A ball bearing 21 cooperates with a reduced portion of the hub 18 to support this member and those just mentioned which are secured to it, in a co-axial rela-

tionship to the main shaft. Also, a second ball bearing 22 supports the middle of the sleeve.

In addition to the drum 16, the clutch 13 also includes two or more clutch shoes 23-23 carried by a clutch spider 24 which is keyed to the main shaft. Coiled springs 25 interposed between the shoes 23 and the spider tend to force the former outwardly into contact with the inner surface of the drum but are not relied upon to produce clutching engagement. These shoes normally are retracted by levers 26 pivoted at 27 on the spider and connected with the shoes by links or draw bolts 27, the outer ends of the levers 26 riding on the inclined surface of a clutch collar 28 which is slidably mounted on the shaft 5. It is operatively connected with a controlling collar 30 arranged to be moved backward and forward axially of the shaft by its connections with a lever 31 fulcrumed on the frame 32 and operated through a sector and pinion with a hand wheel 34, Figs. 1 and 2.

As shown in Fig. 4, the clutch 13 is in its out or inoperative position, but when the hand wheel 34 is operated to move the collar 28 toward the left, the outer ends of the lever arms 26 are allowed to move inwardly and centrifugal inertia then forces the clutch shoes 23 into engagement with the inner peripheral surface of the drum 16. This results in connecting the drum parts 16 and 18 and the bevel gear 10 directly to the shaft 5 and causes them to rotate in unison with said shaft. At this time, therefore, the shaft 6 and the basket to which it is connected through the shaft 9, are positively driven at a speed determined by the ratio of the gears 8 and 10.

The clutch 14 is similar in construction to that above described and includes a drum 36 mounted on a ball bearing unit 37, clutch shoes 38 mounted on a clutch spider 40 and normally held outwardly by coiled springs but arranged to be retracted by levers 41-41 cooperating with a clutch collar 42.

As above indicated, the drum of this clutch is constantly driven from the main shaft through a speed reduction gearing comprising a pinion 43, keyed to said shaft and driving a gear 44 and pinion 45, the latter, in turn, driving a gear 46 and pinion 47 revolving therewith. This pinion meshes with and drives an internal ring gear 48 which is bolted to the end plate of the clutch drum 36.

An interlocking control is provided between the two clutches including a collar 50, Fig. 4, encircling the main shaft and slidably axially of it and operatively connected with the clutch collar 42 through a thrust collar 51 and suitable bearings, as in the common arrangement used with clutches of this type. The collar 50 is pivotally mounted between arms 52, Fig. 1, both secured on a rock shaft 53, and another arm 54, Fig. 4, fast on this shaft is connected by a link 55 to an arm 56 fast on the rock shaft 32 above referred to. Consequently, by properly manipulating the hand wheel 34 one clutch may be thrown in and the other simultaneously thrown out. The adjustment preferably is such that at an intermediate point both clutches are out and the separator A thus can be stopped. It is impossible, however, for both clutches to be in operation at the same time. Fig. 4 shows an arrangement in which the clutch 13 is inactive while the other clutch is in operation and motion is being transmitted from the shaft 5 through the reduction gearing 15 and clutch 14, to the sleeve 12, the spider 40 of the clutch 14 being keyed to this sleeve. At this

time, therefore, the basket of the separator A is being driven at a very slow speed, say for example, 60 R. P. M., which is a typical speed for the discharging operation. At this slow speed, 5 however, the basket is positively and smoothly driven, a result which has not been obtainable heretofore with any gang drive of which I have been able to learn. This positive operation of the basket greatly facilitates the discharging 10 action and is an important advantage from an operating standpoint.

It will be observed that in both these clutches the action of centrifugal inertia on the clutch shoes tends to hold them in their outermost or 15 operative positions. However, this effect is much smaller in the clutch 14, and in order to permit the use of similar clutch constructions in both these mechanisms, it is sometimes desirable to assist the centrifugal action of the clutch shoes 20 with supplemental coiled springs, such as those shown at 58, Fig. 4, to apply additional pressure to the shoes. Preferably these springs encircle 25 guide rods which are connected by links 59 and 60 to one end of a rod 61, the opposite end of 25 which is pivoted to the arm 52. Thus the links form a toggle mechanism which is straightened when the clutch 14 is in its operative position but is broken, and therefore releases the pressure of the springs, when the clutch is thrown out.

30 The bearings for the high speed and low speed connections are mounted on supporting stands 62 and 63, respectively, and both are equipped with casing members 64 and 65 in which the gear mechanisms are housed.

35 In addition to providing the positive slow speed for the discharging operation, as above described, this arrangement also produces the regenerative effect which is an important advantage of any well designed gang drive.

40 Fig. 5 shows a modified construction which may be used in place of the mechanism shown in Fig. 4 for coupling the gear 10 directly to the main shaft 5. This mechanism is somewhat simpler, particularly in omitting the roller bearing unit 17, and it is designed to facilitate manufacture, erection, and repair. It includes many parts corresponding to those illustrated in Fig. 4 and such parts are designated by the same, but primed, numerals. In this arrangement the sleeve 12' is provided with a flanged headpiece 66 which is bolted directly to the end plate of the clutch drum 16'. The gear 10' is made in two pieces, namely, a rim and a hub section, the latter part 10'' being keyed to the sleeve, and the inner 45 races for the two ball bearings 21' and 22' being located at opposite ends of it. All three of these parts are clamped against a shoulder on the part 66 by means of a nut 67. The outer races are 50 held in place by end plates 68 and 70, respectively, 55 encircling the main shaft and bolted to the stationary casing or housing 64'.

In operating any suspended centrifugal, provision must be made to accommodate the gyratory 65 period of operation which the basket goes through in coming up to speed or in slowing down to a stop. For this purpose the operating shaft 6 is connected to the basket spindle 9, Fig. 4, through a flexible coupling, indicated in general at 72. The same coupling, similarly indicated, is shown in Fig. 5 connecting the operating shaft 6' with the basket spindle 9'. Since the latter carries the 70 entire weight of the basket and its load, it is supported in some such mounting as those heretofore used. In the particular arrangement illustrated, a divided spindle is employed, the upper section

9' being secured to a lower section 9" by bolts, and the former is mounted in a sleeve having a spherical section 74 at its upper end which is supported in a spherical bearing socket 75 so that it can gyrate about a point *c* as a center. Upper and lower sets of ball bearings hold the spindle and the sleeve in properly spaced relationship radially and a collar 76 screw threaded on to the outer surface of the sleeve for vertical adjustment, provides a support for a rubber ring 77 which bears against the inner surface of the stationary frame piece 78 and exerts an elastic dampening action on the gyratory motion of the spindle and the parts at the bearing head which oscillate with it.

The operating shaft 6' is supported for rotation co-axially with the spindle 9' in an upper roller bearing 80 and a lower ball bearing 81. It extends downwardly to a point adjacent to the upper end of the spindle and is connected with the latter by the flexible coupling 72 previously referred to.

This coupling comprises a pressed metal casing including upper and lower sections *d* and *e*, Fig. 7, secured together and providing sockets in which relatively thick rubber bushings *f* are mounted. Two of these bushings are connected with the shaft 6' by bolts 82-82, Figs. 6 and 7, extending through a hub portion *b* of the brake drum 7' which is keyed to the shaft 6'. Each of these bolts is encircled by a sleeve or bushing *g*, Fig. 7, which fits tightly in its respective rubber bushing *f*. The other two rubber bushings are similarly connected by bolts 83-83, Figs. 5 to 8, with a collar or nut 84 into which the upper end of the spindle 9' is threaded, as shown in Figs. 5 and 7. These bolts 83-83 also are encircled by bushings *g*.

Thus this flexible connection permits the basket spindle to gyrate about the center *c* in the middle of the flexible coupling while its driving connection with the shaft 6' is positively maintained. In other words, the flexible coupling positively transmits driving torque to the spindle 9', but accommodates relative angular movements of the spindle. Such accommodation is afforded by the elasticity of the rubber bushings *f* and their mounting in such a manner that they are allowed to change shape as required for this purpose.

In order to prevent any relative rotation between the nut or collar 84 and the spindle 9', the central part of the nut is slotted, as shown at 86, Fig. 8, to receive a tapered key 87, and a screw 88 through this key is threaded axially into the upper end of the spindle 9', and locks the key securely in its operative position.

It will be evident that the mechanism shown in Fig. 5 simply takes the place of the corresponding parts of Fig. 4 and is designed to be used in conjunction with the clutch 14 of the latter figure and the gear reduction mechanism for driving it, all as described above in connection with Figs. 1 to 4, inclusive. In addition to providing a somewhat simpler arrangement, the organization illustrated in Fig. 5 also has the advantage of facilitating erection and repair, since the bearings for the shaft 6' and their supports can all be assembled from below and after those parts mounted on and encircling the main shaft have been set in place. Subsequently if repairs are necessary, these parts can be withdrawn downwardly from their normal positions after the basket and its supports are moved out of the way.

While I have herein shown and described a

typical embodiment of my invention, it will be understood that the invention may be embodied in other forms without departing from the spirit or scope thereof.

5 The novel features of the flexible coupling and the mounting of the suspension head for the basket spindle shown in Fig. 5 are not claimed in this application.

Having thus described my invention, what I

10 desire to claim as new is:

1. The combination of a series of upright centrifugal separators, a main horizontal shaft for driving all of said machines, and independent driving mechanisms between said respective centrifugals and said main shaft, each of said mechanisms being constructed and arranged to drive its respective centrifugal from said shaft positively at both a high operating speed and a low discharging speed, and controlling means operable to utilize either of said speeds and to shift from one speed to the other at will.

2. The combination of a series of upright centrifugal separators, a main driving shaft for said separators, means for driving said shaft, and a plurality of two-speed transmission units connecting the respective centrifugals with said shaft and each serving to drive its respective centrifugal positively at a high speed for normal operation and also at a low speed for the discharging operation, and means operable to shift the drive of any of said centrifugals from one of said speeds to the other, at will, and without disturbing the operation of other centrifugals in the series.

3. The combination of a series of upright centrifugal separators, vertical operating shafts for said respective separators, a main horizontal driving shaft, two sets of connections between said horizontal shaft and each of said vertical shafts serving to drive the respective vertical shafts positively at widely different speeds, both sets of said connections including gearing and one set serving to drive the operating shaft at a high speed and the other at a low speed but one of said sets of gearing operating through the other, and controlling means for each separator operable to shift its speed from high to low, or vice versa, at will.

4. The combination of a series of upright centrifugal separators, a main driving shaft for said separators, means for driving said shaft, and a plurality of two-speed transmission units connecting the respective centrifugals with said shaft and each serving to drive its respective centrifugal; each of said units including a supplemental shaft, means including two clutches for connecting said supplemental shaft to said main shaft to be driven therefrom in different speed ratios, and gear connections between said supplemental shaft and the respective separator with which it is associated to drive the latter.

5. The combination of an upright centrifugal separator and a vertical shaft for driving the same, a main horizontal driving shaft for said separator, a sleeve encircling said main shaft, gear connections between said sleeve and said vertical shaft for driving the latter, two clutches arranged to be operated selectively and both driven from said main shaft to drive said sleeve, and a set of reduction gearing between the main shaft and one of said clutches.

6. The combination of an upright centrifugal separator and a vertical shaft for driving the same, a main horizontal driving shaft for said separator, two members revolving around said main shaft, means connecting them with said

main shaft to be driven thereby at different speeds, and two clutches operable selectively to drive said vertical shaft from either of said members at will.

7. The combination of an upright centrifugal separator and a vertical shaft for driving the same, a main horizontal driving shaft for said separator, a gear mounted for rotation around the axis of said driving shaft and having a driving connection with said vertical shaft, means including a clutch for connecting said main shaft and said gear together to drive the latter from the former, a gear mechanism connected with said main shaft to be driven thereby, and means including a second clutch operable to connect said gear mechanism with said first mentioned gear to operate the latter and thereby to drive said vertical shaft through said gear mechanism.

8. The combination of a series of upright centrifugal separators; a main horizontal shaft for driving all of said machines, and independent driving mechanisms between said respective centrifugals and said main shaft; each of said mechanisms being constructed and arranged to drive its respective centrifugal positively from said shaft at both a high speed and a low speed, each of said driving mechanisms including means permitting the respective centrifugals driven thereby to gyrate while still maintaining a positive driving connection with its driving mechanism, and controlling means for each separator operable to utilize either of said speeds at will and to shift from one of said speeds to the other.

9. The combination of an upright centrifugal separator and a vertical shaft for driving the same, a main horizontal driving shaft for said separator, two members revolving around said main shaft, means connecting them with said main shaft to be driven thereby at different speeds, two clutches operable selectively to drive said vertical shaft from either of said members at will, an upright spindle supporting the basket of the centrifugal, means supporting said spindle for both rotary motion with said vertical shaft and also for gyroscopic motion, and a flexible coupling connecting said vertical shaft and said spindle together for the positive transmission of rotary motion from the former to the latter, said coupling being adapted to accommodate the gyroscopic motion of said spindle about a center within the coupling.

10. The combination of a plurality of upright centrifugal separators; a main horizontal shaft for driving all of said separators; and independent driving mechanisms between said respective separators and said main shaft; each of said mechanisms being constructed and arranged to drive its respective separator positively from said shaft at both a high operating speed and a low discharging speed; each of said mechanisms including a supplemental driving shaft telescoped on said main shaft, speed reduction gearing for driving said supplemental shaft from said main shaft, gearing driven by said supplemental shaft and

through which motion from the main shaft is transmitted to its respective separator, and two clutches serving, respectively, to connect said supplemental shaft to said main shaft, one directly and the other through said reduction gearing.

11. The combination with an upright centrifugal separator, a vertical shaft for driving the same and a main horizontal driving shaft for said separator, of a sleeve encircling said main shaft, gear connections between said sleeve and said vertical shaft for driving the latter at a high speed, means including a clutch for operatively connecting said sleeve with said main shaft, a set of reduction gearing between said main shaft and said sleeve for driving the latter and thereby operating said vertical shaft at a low speed, a second clutch through which said sleeve is driven by said reduction gearing, and controlling means operable to utilize either of said speeds at will to drive said separator.

12. The combination with an upright centrifugal separator, a vertical shaft for driving the same and a main horizontal driving shaft for said separator, of gear connections between said main shaft and said vertical shaft for driving the latter from the former at a high speed, a clutch for controlling said driving connections between said shafts, additional driving connections between said shafts including a set of reduction gearing driven by said main shaft and operable through said gear connections to drive said vertical shaft and said separator at a slow speed suitable for discharging the separator, a clutch through which said separator is driven by said reduction gearing, and controlling means for rendering either clutch operative at will to drive said separator.

13. The combination with an upright centrifugal separator, a vertical shaft for driving the same and a main horizontal driving shaft for said separator, of gear connections between said main shaft and said vertical shaft for driving the latter from the former at a high speed, a clutch for controlling said driving connections between said shafts, additional driving connections between said shafts including a set of reduction gearing driven by said main shaft and operable to drive said vertical shaft and said separator at a slow speed, a clutch through which said separator is driven by said reduction gearing, controlling means for said clutches operable to utilize either at will to drive the separator, said means including operating mechanism for one of said clutches for holding it in its power transmitting condition through the aid of centrifugal force created by its own rotation, and said operating mechanism including a toggle for releasably locking the clutch in its power transmitting condition.

14. The combination defined in preceding claim 9, including a brake drum mounted on said vertical shaft above said flexible coupling, and a brake band cooperating therewith.

JOHN F. THOLL.
